UNITED STATES PATENT OFFICE.

OZELLO R. HUNT, OF CHICAGO, ILLINOIS, ASSIGNOR OF ONE-HALF TO WILLIAM VAN MIDDLESWORTH, OF CHICAGO, ILLINOIS.

SPRING STRUCTURE.

1,027,051.

Specification of Letters Patent.

Patented May 21, 1912.

Application filed March 29, 1912. Serial No. 687,030.

To all whom it may concern:

Be it known that I, OZELLO R. HUNT, a citizen of the United States, residing at Chicago, in the county of Cook and State of Illinois, have invented a new and useful Improvement in Spring Structures, of which the following is a specification.

This invention relates particularly to spring structures, such as bed-springs, 10 springs for sofas, cushions, etc.

The primary object is to improve the construction and operation and cheapen the cost of manufacture of spring structures of the character indicated.

15 A further object is to facilitate the assembling operation in the manufacture of a spring-structure having the advantageous characteristics hereinafter set forth.

The invention is illustrated in its preferred embodiment in the accompanying drawings, in which—

Figure 1 represents a broken plan view of a spring constructed in accordance with the invention; Fig. 2, a broken vertical section taken as indicated at line 2 of Fig. 1; Fig. 3, a broken vertical section taken as indicated at line 3 of Fig. 1; Fig. 4, a broken plan view showing a slight modification; Fig. 5, a broken plan view showing another 20 modification; and Fig. 6, a broken elevational view illustrating the manner in which the spiral resilient spacers employed may have their end portions bent or deformed to obviate any tendency to work loose.

35 Referring to Figs. 1 to 3 inclusive, the construction, as there shown, comprises upholstering springs 1 ranged in longitudinal and transverse rows; resilient spacers 2 connecting the upholstering springs in pairs at 40 their end rings; and resilient spacers 3 connecting the upholstering springs in pairs at their intermediate portions. To the end rings of the upholstering springs are connected combination guides and connectors 45 4 which serve to position the resilient spacers with relation to the end rings and connect the spacers to the end rings. The members 4 extend on radial lines from the end rings 50 of the upholstering springs. Each member 4 preferably comprises a U-form member, or clip, having parallel limbs 5 and 6 and a loop, or web, 7 which engages the end ring of the upholstering spring. The limbs 5 and 6 extend away from the end ring and 55 are separated the required distance to enable

them to fit snugly within the resilient spacer 2. The lower limb 5 of each member 4 has its extremity bent to form a downturned hook 8 which is adapted to engage a convolution near the end of the spacer 2. Each 60 resilient spacer 2 is composed of a spiral, or coil-spring of small-gage wire, the coil being of relatively small diameter. In the assembling operation, the extremity of the spiral 2 is caused to engage the hook 8 of the 65 connector 4, and the spiral is turned or threaded onto the connector, the limbs 5 and 6 of the connector being received inside of the convolutions of the resilient spacer. Thus, a pair of convolutions of the coil- 70 spring 2 will be confined between the hook 8 and the end ring of the upholstering spring. The distance between the hook 8 and the loop 7 of the connector may be such that the intervening convolutions will be 75 compressed between the hook 8 and the end ring of the upholstering spring, so that the friction will be sufficient to prevent the spring 2 from unturning. It may be ex- 80 plained, that in the assembling operation it is necessary to screw the end portion of the coil-spring 2 some distance past the end ring of the upholstering spring, so that in a reverse turning operation the opposite end of the spring 2 may be caused to spirally 85 engage the connector 4 at the other member of the pair of upholstering springs which are being connected. The springs 2 are preferably disposed diagonally and across each other in pairs, having spiral engage- 90 ment with each other at the intersecting point, as indicated at 9; that is, one spring 2 is screwed through the central portion of the other at right-angles thereto. Thus, the upholstering springs are resiliently tied to- 95 gether, and are also resiliently held apart or spaced with relation to each other. The resilient spacers 3 are similar to the resilient spacers 2, but are of somewhat greater length, where the upholstering springs are 100 of the hourglass-form shown. Inasmuch as the spacers 3 connect the intermediate portions of the upholstering springs, it is pre- 105 ferred to arrange the spacers 3 in line with the rows of springs. Connectors like the connectors 4 may be employed to connect the coils 3 to the intermediate portions of the upholstering springs; or U-form connectors 4^a having limbs 5^a and 6^a provided, respectively, with hooks 8^a and 8^b may be 110

employed, as shown in Fig. 3. In such case, the limb 6^a is made shorter than the limb 5^a by a distance equal to substantially the pitch (or a multiple thereof) of the coil-spring 3, so that while one convolution of the spring 3 engages the hook 8^a, another convolution will engage the hook 8^b. The parts may be so proportioned, however, that the convolutions of the spring 3 will be somewhat dis-
10 torred and forced into spiral engagement with the hooks, so that the frictional engagement will be increased. Here again, the end convolution of the spring 3 is forced into engagement with the intermediate convolution
15 of the upholstering spring 1, so that the upholstering springs are resiliently tied together and also resiliently held apart.

In the modification shown in Fig. 4, the upholstering spring 1^a has its end ring offset or struck outwardly at points 10, the offsets thus afforded being adapted to receive the loop portions of the connectors 4^b. The connectors 4^b are of the same form as the connectors 4, and aside from the fact
25 that the loop portions of the connectors 4^b engage the offsets 10 of the end ring, the springs 2 are connected with the spring 1^a in the same manner as the springs 2 are connected with the springs 1. It will be noted
30 that the offsets 10 are adapted to prevent the connectors from slipping on the end rings, and thus to prevent the coil springs 2 from slipping around on the end rings of the upholstering springs. For ordinary
35 purposes, however, the offsets 10 are unnecessary.

In the modification shown in Fig. 5, a resilient spacer or coil-spring 2 is shown connected with the end ring of the upholstering
40 spring 1^b by means of a connector 4^c. The connector 4^c is of the same construction as the connector 4, and the connection is made in the manner shown in Fig. 2, except that the spring 2 is caused to project somewhat
45 into the end ring. That is to say, the coil-spring is caused to spirally engage the end ring of the upholstering spring both on its convex surface and on its concave surface, thus increasing the frictional engagement
50 between the members.

In the modification shown in Fig. 6 a coil-spring 2 is connected with the end ring of the upholstering spring 1^c in the manner shown in Fig. 2, but the extremity of the
55 end convolution of the spring 2 is deformed or bent, as indicated at 11, to prevent the spring 2 from unscrewing or working loose.

In each of the described constructions, the
60 connector employed is horizontally disposed, but has its limbs lying in a vertical plane, and it will be observed that the connector serves to position the resilient spacer with relation to the plane of the convolution of the upholstering spring where the connection is made. Thus, in Fig. 2, it will be

understood that the upper portion of the coil-spring 2 is disposed only slightly above the plane of the end ring, so that there is no objectionable projection, such as would tend to injure a mattress or pad placed on the
70 spring structure.

Ordinarily, it will suffice to connect either the end rings of the upholstering springs or the intermediate convolutions of the upholstering springs by resilient spacers.
75 Thus, either the springs 2 or the springs 3 may be dispensed with, if desired. In the construction of cushions for automobiles or the like, it may be desirable to connect the intermediate portions of the upholstering springs as shown in Fig. 2 and omit the end ring connections shown in Fig. 2. In any case, however, the upholstering springs may be individually compressed without substantial distortion of the surrounding
80 springs, inasmuch as the resilient spacers will yield freely to permit such compression. At the same time, the resilient connecting coils will aid in righting the compressed springs after the pressure is relieved.
85

The improved construction results in a very substantial saving of wire, since the connectors employed for joining the resilient spacers to the upholstering springs
90 may be very short. Again, this construction affords very secure connections between the resilient spacers and the upholstering coils; and the assembling operation is readily performed. Where the spacers 2 are diagonally disposed and interlocked at their central
95 portions, as shown in Figs. 1 and 2, they serve to fill the spaces between the end rings of the upholstering springs.
100

The foregoing detailed description has
105 been given for clearness of understanding only and no undue limitation should be understood therefrom, but the appended claims should be construed as broadly as
110 permissible in view of the prior art.

What I regard as new, and desire to secure by Letters Patent, is—

1. In a spring structure of the character set forth, the combination with upholstering springs provided with end rings, of connectors on said end rings having guide portions and hook portions, and small coil-springs having convolutions embracing said guide portions and engaging said hook portions and also engaging said end rings.
115

2. In a spring structure of the character set forth, the combination with upholstering springs, of connectors engaging the upholstering springs and extending away from the same, and small coil-springs having convolutions engaging said connectors and engaging the upholstering springs, said connectors having means for exerting tension on said coil-springs.
120

3. In a spring structure of the character
125

set forth, the combination with upholstering springs, of clips having hooked engagement with the upholstering springs and extending away from the same and provided 5 with hooks turned toward the springs, and small coil-springs having convolutions embracing said clips and engaging the upholstering springs and the hooks of said clips.

4. In a spring structure of the character 10 set forth, the combination with upholstering springs, of U-form connectors having web portions engaging the upholstering springs and provided with convolution-engaging hooks, and small coil-springs having 15 convolutions embracing the members of said U-shape connectors and confined between the upholstering springs and said hooks.

5. In a spring structure of the character 20 set forth, the combination with a pair of upholstering springs, of U-form wire clips having limbs separated by a space, a limb

of each connector provided with a curved end affording a hook, and a small coil-spring having convolutions at each end portion embracing the limbs of the connector thereat 25 and confined between the upholstering spring and the hook on said limb.

6. In a spring structure of the character 30 set forth, the combination of a pair of upholstering springs provided with end rings, of a pair of U-form connectors having webs 35 engaging said end rings and having straight upper limbs and lower limbs provided with downcurved extremities, and a small coil-spring having convolutions at each end embracing a connector and engaging an end ring and the co-acting hook.

OZELLO R. HUNT.

In presence of--

JOHN WILSON,
R. A. SCHAEFER.
